UNITED STATES PATENT OFFICE.

GEORGE MARSHALL CLARK, OF HIGGANUM, CONNECTICUT.

DISK HARROW.

SPECIFICATION forming part of Letters Patent No. 514,208, dated February 6, 1894.

Application filed October 19, 1892. Serial No. 449,379. (No model.)

To all whom it may concern:

Be it known that I, GEORGE MARSHALL CLARK, of Higganum, in the township of Haddam and county of Middlesex, in the State of Connecticut, have invented certain new and useful Improvements in Disk Harrows; and I do hereby declare that the following specification, taken in connection with the drawings furnished and forming a part of the same, is a clear, true, and complete description of my invention.

My said improvements have been devised with special reference, to affording a disk harrow, adapted to operate within a wide range of requirements, including all of those which are ordinarily involved, and some others, which as I believe, have never before been provided for in such machines. In my present machines, disk gangs having gang frames are employed, and, broadly stated, one feature of my invention consists in the combination with gangs, and their frames, of a pole, and a head plank rigidly attached cross-wise to the pole, at right angles thereto at its rear end, and provided with numerous variably located bolt seats or bolt connections which enable the gangs to be variably adjusted as follows: angularly to the line of draft and inclined in either direction, or at right angles thereto; also, to be located closely adjacent to the pole, and with their inner ends either considerably separated, or closely adjacent to each other; and also, so that either or both gangs may be located variably remote from the pole; and, still further, so that the gangs may be reversed in any of said positions, and operated so as to effect either an outward, or an inward displacement of soil.

In their simple and inexpensive forms, my machines involve separately located bolt seats, afforded by simple holes for receiving bolts, which secure the gang frames to the head plank; and for making angular adjustments of the gang frames, and reversals of the disk gangs, the separate manipulation of each gang is required, as well as of its bolts; but my machines in some of their best forms, embody draft bars, which are connected with the pole, and also directly connected with the disk gang frames, so that both gangs may be swung simultaneously, into, and out of working adjustment; also so that reversals of the gangs

when located near the pole, can be accomplished without changing the connections of the draft bars with the gang frames, whether the latter be pivoted at one end thereof, or at the other, to the head plank. When one or both of the disk gangs are located at the outer end or ends of the head plank, their reversal involves at each gang, a shifting of the bolt seats, or, in other words, the bolt connections with the head plank, and also those which connect with the draft bars. With only one of the gangs located remotely from the pole, and the other located near the pole, the machine is adjusted at what I will term "half extension," the "full adjustment" being made by having both gangs located as remotely from the pole as is possible, and under either of these several last named adjustments, which I believe to be novel in a disk harrow, the gangs may be effectively operated beneath low lying branches of trees, as in orchards and orange groves, and to effect an outward or an inward displacement of soil, more or less closely adjacent to the trunks of the trees, and to perform this work without liability of injury to the foliage, flowers, or fruit of the overhanging branches, either by contact with the machine, the driver, or the team.

The disks in my machines, may be of any of the well known concavo convex forms, and whether solid, or made up of separate plates, but the best results will accrue from the use of such disks as have blades, with tangential working edges, as heretofore patented to me, the edges of the blades now used, being tangential at both the front and rear; this being important in a reversible bladed disk, so that in either adjustment, the front cutting edge will be tangential to the central working face, the outer edge of each blade being concentric with the axis of the disk. For specially adapting my machines for working the sides of planted rows, each gang has at one or both ends, a disk which is larger in diameter than the other disks in the gang.

I am aware that it is not new to embody in one gang, a series of disks graduated in diameter, from a large disk at one end, to a small disk at the other end of the gang. The axles of such gangs were not only inclined to the line of draft, as in my machines, but also

with respect of a horizontal plane; or in other words, inclined downwardly from the large to the small disks, so that the latter would penetrate the soil as deeply as the larger disks. 5 In my machine, the one or the two large disks at the end or ends of a gang do, and are designed to cut more deeply into the soil than all of the others, these latter being uniform in diameter, and the gang axle being always 10 substantially horizontal, or at least when in service, being always parallel with the surface of the ground underlying it. I have also devised a simple form of clod breaker, which like those heretofore patented to me, are so located between the disks, as to render it practically impossible for roots, grass and weeds to get wrapped around the axle. My improved clod breakers, are metallic straps, suspended from the gang frame, and are in 15 front of, and at the rear of the axle, and also underlie the axle, thus rendering them especially well adapted for use with reversible disk gangs, and those straps which are between the disks, where the bearings are located, serve not only as clod breakers, but also 20 as reliable lateral braces for the journal box hangers or standards.

After describing my improved machines, as illustrated in the drawings, the features 30 deemed novel, will be duly specified, in the several clauses of claims hereunto annexed.

Referring to the drawings—Figures 1 and 2, illustrate one of my machines in its best form, in plan view, and rear elevation, and as when 35 adapted to ordinary service, but with the gangs set on a line at right angles to the pole, as for transit to and from a field. Fig. 3, illustrates the same in plan view, as when adjusted for actual service, the disks being so 40 arranged as to effect an outward displacement of soil, and with the inner ends of the gangs as near together, as is practicable with this machine. Fig. 4, illustrates the same in plan view, with the gangs set for 45 effecting an inward displacement of soil. Fig. 5, illustrates the same in plan view, but with the gangs arranged for inward displacement, but pivoted at their outer ends, and affording a somewhat wider space between 50 the inner ends of the gangs, than when the gangs are pivoted at their inner ends, as in Fig. 4. Fig. 6, in plan view, illustrates the machine adjusted for outward displacement, but otherwise as in Fig. 5. Fig. 7, in plan 55 view, illustrates the machine with one of its gangs adjusted as in Fig. 6, and the other widely separated therefrom, and as remotely from the pole, as possible, this being what may be termed a "half extension" adjustment, 60 with both gangs set for outward displacement of soil. Fig. 8, in plan view, illustrates the machine at half extension adjustment, and with the gangs arranged for inward displacement. Fig. 9, in plan view, illustrates the machine at full extension adjustment, with the gangs arranged for outward displacement. Fig. 10, in plan view, illustrates the full ex-

tension adjustment with the gangs arranged for inward displacement. Fig. 11, is a cross vertical section of the machine, on line *x*, Fig. 2, showing the relations of one of the clod breakers, to a journal box, and its hanger or standard. Fig. 12, is a cross vertical section, of the machine, on line *y*, Fig. 2, showing the relations of the clod breakers to the gang frame, and the gang axle. Fig. 13, illustrates the construction of the clod breakers in two parts, each connected at its lower end with the journal box shell or casing. Figs. 14 and 15, in plan view, illustrate my machines specially adapted for working the sides of planted rows, the gangs being adjusted respectively, for inward and outward displacement of soil, each gang having a large disk at the inner end (in Fig. 15, at both ends), and the gangs 85 being more widely separated at their inner ends, than when adjusted as in Figs. 4 or 5. Figs. 16, 17 and 18, in two top views, and a vertical central section, illustrate one end of a head plank, with a single bolt seat or hole, 90 capable of being shifted from either position of adjustment, to the other. Figs. 19 to 26 inclusive, in plan views, illustrate one of my machines in its most simple and inexpensive form, the several adjustments illustrated, corresponding with those shown respectively in Figs. 3 to 10 inclusive.

I will first describe my machine, as illustrated in Figs. 1 to 10. The machine thus shown, is provided with a pole *A*, for use with a double team, but when one horse machines are desired, an appropriately small number of disks are employed, usually four in a gang, and the thills are connected with a cross bar, bolted to a pole butt, which corresponds with the rear portion of this pole *A*, and in either case, attached firmly to a head plank or gang coupler beam, *B*. The coupler beam is preferably composed of hard wood, in the form of a plank, although it can be made of metal, in which case its contour, thickness, and lateral dimensions may obviously, be quite unlike those of the wooden beam shown. This head plank, may be only short enough to serve as a support for the pole, and as a coupler beam 110 adapted to admit of a reversible adjustment of the disk gangs *C*, *C'*, without departure from certain portions of my invention, but in machines embodying my extension improvement, the head plank should at least, be as 115 long as the combined length of the two gang frame planks *a*, to which the journal box standards *b*, are connected. Each gang frame *a*, is provided with five vertical bolt holes, one in the middle at *a'*, and others at each end 120 as at *a²* and *a³*, with intermediate holes as at *a⁴* and *a⁵*, and still other holes therein afford entrance to the hollow standards *b*, within which suitable lubricant is carried. This head plank *B*, affords a wide or full extension 125 adjustment, and it is provided with several sets of bolt seats, or holes, or openings. The large holes or openings *c'*, and *c''*, intermediate between the pairs of bolt seats, at each 130

side of the pole, afford free spaces, for long vertical bolts c , having sleeves c^3 , (see Fig. 12) by means of which, the draft bars or links, D, D' , are directly coupled to the gang planks a , the sleeves permitting the firm clamping of the gang planks, with or to, the draft bars, without unduly binding the intervening head plank B . The two draft links D, D' , are laterally braced with reference to each other, by means of a brace bar, D^2 , which overlies, and rests on the pole, and is coupled at its ends, to the draft bars, by means of bolts in the latter, and elongated bolt holes in the bar, as clearly indicated. The series of holes d', d^2, d^3, d^4 , in the head plank are in line with each other, and each serves as a seat, for one or the other of two pivot bolts d , by means of which the gang frames and their planks a , are swiveled, hinged, or pivoted to or upon, the head plank B , and provide for certain adjustments of the gangs, as will be hereinafter fully described, as well as those pertaining to the second line, or series of bolt seats, or holes d^5, d^6, d^7 , and d^8 , which also at times receive said bolts d . These bolt holes being in pairs $d' d^5, d^2 d^6, d^3 d^7$, and $d^4 d^8$, afford shifting bolt seats, which will register with appropriate bolt seats in the gang frame, it being necessary for effecting a reversal of a disk gang, that the bolt d , should occupy a differently located seat, and hence it is immaterial, so far as this shifting capacity is concerned, whether the different bolt seats are afforded by two separate holes in the head plank, or by a single hole, which can be so shifted, as to occupy either of the two positions, which are afforded by a pair of bolt holes, as will be hereinafter more fully indicated. The several holes e , in the head plank, serve as mere ducts, or entrances to the hollow standards b , through or from which, lubricating matter is supplied to the disk gang journal boxes. Several of these holes are required, and when either one of them registers with the lubricating chamber of a standard, it is closed by means of a plug e' , the plugs being transferred to the corresponding holes in the gang frames, when the latter are projected beyond the head plank. The draft bars D, D' , at their front ends, are strongly coupled by means of links f, f' , one above, and the other below the pole, and connected with the arms by bolts f^2, f^2' . These two links, have each a centrally located hole, and the pole at that point, is centrally provided with several holes f^3 , in line with each other, and lengthwise of the pole, so that either of these holes may be occupied by a locking pin g , which is long enough to pass through the pole, and occupy both of the holes in the two links f, f' . A hand lever E , pivoted to a base which is bolted to the upper side of the pole, is connected by rods or links h, h' , with the bolts f^2, f^2' , at the forward end of the draft bars D, D' , thus providing for throwing the gangs into and out of working position. A seat stand socket F , of the usual form, is mounted on the rear end

of the pole, for receiving the spring standard of a driver's seat F' , the latter, occupying a position which will enable the driver to readily displace and apply the locking bolt g , and to operate the hand lever E . The disks G , are shown to be in gangs of six each, but it is obvious that the number may be largely varied, some of my one horse machines, as before stated, having but four disks in a gang, and some of the large machines having eight, ten and even twelve disks in each gang. Said disks as hereinbefore indicated, may be also varied as to diameter, and they may be plain concavo convex disks, but as shown, they are bladed disks, and embody features disclosed in my Letters Patent No. 369,163, dated August 30, 1887, in that the blades have front cutting edges i , which are tangential to the central earth working surface, and they have outer cutting edges i' , which are concentric to the axis of the disk. These disks being reversible, are provided with blades which have two tangential working edges i and i' , one or the other of which, is for the time being, the front working edge of the blade, according to the adjustment of the gang, for effecting an outward, or an inward displacement of soil.

For adapting the machine under certain adjustments to operate with special reference to rows of young crops, one (or both) of the end disks of each gang, is larger in diameter than the others, so that whether adjusted for outward or inward displacement, there will be an extra working of the soil at the two sides of a row, as will be hereinafter more fully described. The gang axles H, H' , consist as heretofore, of a central rod, and sleeves or spools between the disks, and they are provided with tight wooden journal boxes, constructed in accordance with disclosures in my Letters Patent No. 478,311, dated July 5, 1892, and, as therein described, the boxes are longitudinally confined, and arranged to receive at their ends, the end thrusts, of the axle, incident to the operation of the disks. The hollow standard b , as in my prior machines, serve as reservoirs for a suitable lubricant, which, entering the top of the box centrally, works its way downwardly and outwardly, to the ends of the boxes, effectually preventing the inward passage of grit and dirt. The axle journals, are flanged spools or sleeves provided with collars k, k' , so that the end thrust bearings, are between the inner surfaces of the collars, and the ends of the boxes, the grain of the wood in the latter, being presented endwise, and affording a specially desirable bearing surface, and especially when floured plumbago is used as a part of the lubricant employed. In my present machines, I employ between the disks double clod breakers I, I' , which involve certain features heretofore patented to me in this connection, in that the clod breakers of Figs. 1 to 12 are suspended, and extend to and beneath the axle, and effectually guard against the

balling or wrapping of roots, weeds, and grass around the axle, as disclosed in my Letters Patent No. 444,662, dated January 13, 1891. In this machine, the clod breakers I, as specially shown in Fig. 12, are of a novel form, and being double, are specially suited for reversible gangs, each double clod breaker being a suspended bow shaped metal strap, secured to the two edges of the gang frame plank a, and so as to hang in front and at the rear of the axle, and with the lower end beneath the axle. These clod breakers may be rigidly attached, but when loosely mounted, so that they may vibrate to and fro, they are less liable to retain soil on their upper surfaces near the axle, and are better able to discharge the trash liable to be caught thereon. The clod breakers I', are located in line with the box standards b, at the front and rear thereof, and while they operate like the clod breakers I, they also serve as lateral braces for the standards, because they are fitted to snugly engage with the under side of the box casing, as shown in Fig. 11, and sometimes they are pinned or otherwise locked thereto, and also securely attached to both edges of the gang frame plank a. In working on stony ground, the clod-breakers I', as thus constructed, often enable the box standards to override boulders which might otherwise by shock therewith, severely strain the machine. All of the advantages, except the last, will accrue, if the clod breakers be constructed in two parts, as at I², one for each side, and each provided at its lower end, with a point or hook, for snugly engaging with an eye l, as illustrated in Fig. 13. This arrangement, involves that portion of my invention, which consists in the combination with the box casing, and standard, of clod breakers, which are pendent from both edges of the gang plank, and are firmly connected with the box casing or the standard.

Referring now to Figs. 1, and 2, it will be seen that the two disk gangs C, C', are arranged at right angles to the pole, as when moving the machine from place to place, and that the convex sides of the disks, are toward the pole. The gangs are set with their inner ends, as near to each other as is practicable in gang frame machines, and as here shown, the machine is arranged for the performance of ordinary duty, with an outward displacement of soil. The hand lever E, is inclined rearwardly, and the locking pin g, is in place. The pivot bolts d, d occupy the holes d² and d³ in the head plank, and the draft-bars D, D', are directly connected through the holes c' and c², centrally with the gang frames. Now, upon removing the locking pin g, and throwing the hand lever E, forwardly, the two disk gangs will be inclined to the line of draft, as shown in Fig. 3, the degree of inclination being determined by whichever of the several holes f³, in the pole may be occupied by the locking pin g, for uniting the draft-arms to the pole. Now if an inward displacement of soil is required, the disk gangs, may be re-

volved or swung around on their bolts c, without disturbing the connections of the gangs with the draft arms, the only change required from the last adjustment, being first, the removal of the pivot bolts d, d, and after swinging the gang frames, said bolts are inserted into the holes d' and d', in the head plank as illustrated in Fig. 4. In this case, when the machine is adjusted for the road, the hand lever E, is inclined forwardly, and hence pulling it rearwardly, sets the gangs into their inclined or working positions, and they are then confined therein, by the locking bolt g. When operated as thus adjusted, there is but little unworked soil between the inner ends of the gangs, and this is the mode of working, which is most generally required. It will be now seen, that with reference to the adjustments shown in Figs. 3 and 4, only the central portion of the head plank B, is applied to actual service, as a coupler beam, and also as a support for the pole, thus uniting the two gangs, and affording their pivotal connections. It is therefore to be understood, that the feature of my invention, which includes the direct connection of the draft bars with the gang frames, and a head plank which enables the gangs to be reversed, without disconnecting the draft arms, is in no manner dependent upon a long head plank as shown, although such a head plank is desirable and useful, even independently of the full extension feature, because it enables the gangs to be more widely separated at their inner ends, when in working position, whether for outward, or inward displacement of soil. As, for instance, as shown in Fig. 5. In this adjustment, the gangs are arranged for inward displacement, but instead of being pivoted to the head plank at their inner ends, their pivot-bolts d, d, occupy holes d' and d', near the outer ends of the head plank. The draft arms, as before, are connected centrally with the gang frames, and hence when the gangs are inclined for service, their inner ends, swing away from each other and afford a central width of un-worked soil, or a strip, in which young plants may be growing.

For adjusting the machine to effect an outward displacement of the soil, it will be only necessary to reverse the pivot bolts d, swing the gangs around, and insert the bolts, this time in the holes d² and d³, as shown in Fig. 6.

For working under the low lying branches of trees, in an orange grove, for instance, it is sometimes specially desirable to also thoroughly work the central space between the rows of trees, and for this purpose, only a half extension adjustment will be required. In this case, one of the gangs remains in its normal position, and the other is centrally pivoted near the appropriate end of the head plank. As for instance, when adjusted for outward displacement, as shown in Fig. 7. In this case, the non extended gang C', is pivoted as in Fig. 6, but the gang C, is located with its center, beneath the outer end of the

head plank, and is pivoted thereto, its bolt d , occupying the bolt seat or hole d^8 in the head plank. In making this adjustment, however, the draft bar D , is connected with the inner 5 end of the gang, as clearly shown. If the machine is to be then adjusted, for inward displacement, and remain at the half extension adjustment, no disconnection is required between the draft bar D' and the gang C' , but 10 the pivot bolt d , is removed, the gang then being swung around, and the bolt d , then inserted in the hole d' . For reversing the gang C , the draft arm D , must be disconnected, the pivot bolt d , transferred from hole d^8 to hole 15 d^4 , the gang swung around, and the draft bar D , then reconnected with the inner end of gang frame, as shown in Fig. 8.

Now for adjusting the machine for working under its "full extension" capacity, both 20 gangs are arranged for outward displacement, as shown in Fig. 9, each gang extending nearly half of its length beyond the ends of the head plank, and enabling the machine to operate at each side, in an orchard or grove, beneath 25 low hanging branches of two rows of trees, and to throw soil toward the trees; or when adjusted as shown in Fig. 10, to displace soil away from them. Now, taking any one of 30 the adjustments shown in Figs. 3—4—5 and 6, it will be seen that the reversibility of the gangs, involves no change whatever, as between the draft arms and the gang, and only an appropriate shifting of one pivot bolt, at 35 each gang. Also, that the adjustments to half extension, as in Figs. 7 and 8, leaves one gang as before, but with a shifting of its pivot bolt, and the other gang requires a shifting of the pivot bolt seat, as well as a shifting of the draft bar connection. For reversing the 40 gangs, however, one bolt connection in one gang, is rearranged, and at the other gang, both bolts are shifted, and both bolts must be shifted in reversing the two gangs, in either 45 of the full extension adjustments of Figs. 9 and 10.

As hereinbefore indicated, my machines, when adapted to operate with special reference to working the sides of rows of young crops, are provided with gangs, having at one 50 or both ends, disks which are larger in diameter, than the others in the same gang, as illustrated in Figs. 14 and 15; wherein the gangs are respectively adjusted for an inward, and an outward displacement of soil. In these 55 adjustments, the inner ends of the gangs are much more widely separated, than when arranged as shown in Figs. 4 and 5, because the connection of the gangs to the head plank, and to the draft bars, is effected by locating 60 the bolts c , c , and d , d , in the intermediate holes a^4 and a^5 , of the two gang planks. For securing an inward displacement of soil, the pivot bolts d , d , as shown in Fig. 14, occupy the 65 holes d' , and d^4 , in the head plank, and for securing an outward displacement, said bolts d , d , occupy the head plank holes d^5 , and d^8 , as shown in Fig. 15, the bolts c , c , in either adjust-

ment, occupying the large holes c' , and c^2 , in the head plank. The end disks G' , G' , in each instance, are from two to four inches larger 70 in diameter, than the other disks G , in the same gang, and therefore the soil in the lines of the two inner ends of the gangs, will be worked more deeply than by the small disks, and weeds and grass adjacent to planted 75 rows will be effectually cut up by the large disks, and turned beneath the heavily displaced soil.

Although each of the several adjustments described, will be at times required, whether 80 the disks in each gang be of one size, or not, the adjusted separation of the inner ends of the gangs, as shown in Figs. 14, and 15, will have its prime value, when the gangs have 85 large disks at their inner ends. When each gang has a large disk at one end only, the reversal of the gangs will only be practicable when the large disks are not needed at the inner ends of the gangs, but when the gangs have a large disk at both ends, as in Fig. 15, 90 the reversal thereof will be effected, as when the disks are all of one size. If large disks 95 are used at both ends of each gang, the disks at the outer ends, will not operate adversely to good cultivation, but their use will only be warranted, with a view to affording a reversal 100 of the gangs. The organization in a gang of disks, of an end disk, larger in diameter than the others, is a novel feature of practical value, and it involves one portion of my present invention.

In both of the forms of machine shown, the separately located bolt seats, in the head plank, afforded by the holes designated d' , d^5 , or d^2 , d^6 , or d^8 , d^1 , or d^4 , d^8 , in the arrangement and 105 location with respect of the pole and of the centrally located holes, at c^4 , in the head plank, involve matters which are essential in machines embodying that portion of my invention, which enables the disk gangs to be 110 operated for close working, and at half extension, as well as at full extension. The requirement for shifting the several bolts from one line to another, is most economically provided for, by the use of separate bolt holes, 115 in pairs as shown, but should slightly increased cost in construction be ignored, the shifting of the bolt seats, as well as the positions of the bolts, at either one or all of the several points, where pairs of holes are located, may 120 be accomplished without detaching the bolts at all. As, for instance, as illustrated in Figs. 16—17 and 18—A large circular hole is 125 cut in the head plank, of sufficient size or diameter, to include the two bolt holes of a pair, as well as the speed between them, and at the upper side, this opening is recessed or annularly rabbeted as at m , Fig. 18. In this recess a circular turn block n , is rotatively mounted, and securely retained therein by 130 means of a cap plate n' , bolted securely to the head plank, and having a circular hole somewhat smaller than the turn block, so as to afford an ample overlying retaining flange, as

indicated at n^2 . The turn block has a single bolt hole, as at m' , the lower portion of which is within a lug m^2 , integral with the turn block, so as to afford an effective strong seat 5 for the shank of the bolt. A strong adjusting arm m^3 , is securely hinged to the top of the turn block, and at its center, and the cap plate has two pairs of upwardly projecting lugs at n^2 , and n^3 , the space between the lugs 10 in each pair, being such as to snugly receive, and hold, the adjusting arm m^3 . With a disk gang and frame, secured to the head plank by means of the bolt d , the latter without any direct manipulation thereof, can be 15 shifted; for instance, from the position of bolt hole d^4 , to that of d^5 , by an appropriate rotative movement of the turn block, by means of its adjusting arm, and securely confined in position, by placing the latter in the 20 custody of the appropriate pair of lugs n^2 , or n^3 . Now while there is but one bolt hole in the turn block, and while the shifting of the bolt may be accomplished without manipulating the bolt itself, this organization affords 25 as a matter of fact, two separately located bolt seats, for the reception of bolts for variably coupling a disk gang frame, to a head plank, and hence, when employed in my machines, I deem this complex arrangement, to 30 be an equivalent of the simple pairs of shifting bolt seats or holes, so far as relates to an effective, variable working adjustment of the disk gangs, with relation to the head plank, and to the pole; and although by reason of 35 its complexity, and by a manipulation of the lever arm of the turn block, an actual displacement and replacement of the bolt is rendered unnecessary, I nevertheless, prefer that the separately located bolt seats near the 40 ends of the head plank, and near the pole should be afforded by the pairs of bolt holes.

It will be obvious, that in the machine Figs. 1 to 15, the rear ends of the draft arms, afford shifting bolt seats, the latter being sometimes 45 located near the rear sides of the large holes in the gang plank, and at other times, near the front sides of said holes, so that in point of fact, the longitudinal movement of the draft arms, effects the same shifting of the bolt seats, as would result from the use of turn blocks, as described.

A characteristic feature of my machine, considered merely as a reversible harrow, is its capacity for a reversion of the gangs, by the 55 simple displacement, and replacement of a single connection at each gang, or, in other words, shifting the seats of the pivot bolts d . In a non-extension, close working harrow, this feature may obviously be embodied by the 60 use of a short head plank, and (instead of the small sleeves c^6 , around the bolts c), using blocks of wood or metal, slightly thicker than the head plank, and to thereby maintain the same good connection, (as afforded by the 65 sleeves) between the draft bars and the gangs, and also enabling the surface of the head plank at its ends, to support the draft bars

against undue deflections from torsional or twisting movements of the gang frames.

My machine as thus far particularly described, is far from expensive, is effective, and can be conveniently operated, but it is to be understood that simpler and less expensive machines can embody many of the valuable features of my invention, and especially 70 those pertaining to the "full" and the "half" extension capacities, even if the draw bars be rigidly and permanently coupled to the pole, and to the head plank, provided the latter, and the gang frames have appropriate bolt 75 seats, or connections, which will enable the gangs to be located and adjusted, in the various ways described, and readily reversed. Such a machine, is shown in Figs. 19 to 26 inclusive. The pole A, of this machine, as 80 before described, is in each of these figures, shown to be rigidly connected with this head plank B', but these draft bars D³, are rigidly bolted both to the pole, and to the head plank, the latter having as before described, the several 85 separately located bolt seats afforded by the bolt holes d' , d^2 , d^3 , d^4 , d^5 , d^6 , d^7 and d^8 , and similar oiling ducts or holes e . Instead of having two large intermediate holes, as in the other head plank, this one has at the same 90 points, and within the same area of space, holes as at c^4 , c^5 , these being small holes because of the necessity for a confining capacity at the head plank, which in the other machine, is afforded by the draft bars. The disk 95 gangs C, C', are as before described, each of the gang frame planks a, having the same five bolt holes, one in the middle, one at each end, and the intermediate holes. As all of the gang working strain in this machine, is 100 borne by the head plank, at the pivot or locking bolts d , and c^5 in lines somewhat liable to split the plank, it is well to reinforce the 105 bolt holes with metal straps, as at l' , each having bolt holes therein, and the strap being so shaped, as to well engage with the edges of the head plank. The disks, the standards, and the clod breakers, are all as before described.

Referring now to Fig. 19, it will be seen 115 that the two gangs are hinged at their inner ends, to the head plank by the bolts d , occupying the bolt holes d^2 and d^3 , and that if the bolts c^5 , should be located in the holes d' and d^4 , the adjustment would be as in Fig. 1, but 120 the bolts c^5 being in holes at c^4 , and in the middle holes of the gang frames, the adjustment corresponds with that shown in Fig. 3, and it is obvious that this machine could 125 perform the same kind of work, and in the same way, as the more expensive, and more convenient machine, first described. In like manner it will be seen, that the adjustment shown in Fig. 20 corresponds with that of Fig. 4; Fig. 21, with Fig. 5; Fig. 22, with Fig. 130 6; Fig. 23, with Fig. 7; Fig. 24, with Fig. 8; Fig. 25, with Fig. 9, and Fig. 26, with Fig. 10. A machine of this form, in common with that first described, embodies all of the features

of my invention, except such, as include that direct coupling of the draft arms, with the gang frames.

Although I have shown no scrapers for the disks, it is obvious, that they may be applied as heretofore, to either, or both edges of the gang frame.

Having thus described my invention, I claim as new and desire to secure by Letters to Patent—

1. In a disk harrow, the combination substantially as hereinbefore described, of a pair of disk gangs, and gang frames, each having several vertical bolt seats or holes; a pole; a head plank overlying the gang frames, rigidly connected with the pole and provided with variably located or shifting bolt seats, near the pole at each side thereof, and also at the outer ends of the plank, and other intermediate located bolt seats or holes, and a pair of bolts for each gang frame, adapted to occupy such appropriate holes or bolt seats in the head plank, as will register with appropriate bolt holes or seats in either gang frame, the organization being such that by a shifting of the position of the bolts, either or both disk gangs may be located near to or variably remote from the pole, either at right angles thereto, or inclined therefrom in either direction, and to be reversely adjusted with reference to either an outward, or an inward displacement of soil.

2. In a reversible disk harrow, the combination substantially as hereinbefore described, of a draft pole, a head plank rigidly coupled to said pole at right angles thereto; a pair of disk gangs and gang frames, pivot bolts adapted to occupy appropriate seats or holes in the head plank and to occupy also other holes in the gang frames according to the desired adjustment of the disk gangs with reference to the outward or inward displacement of soil, and draft bars connected with the pole, and also directly connected by means of bolts with the gang frames, the organization of these parts being such that a reversal of the gangs requires only the shifting of a single bolt at each gang.

3. In a disk harrow, the combination substantially as hereinbefore described, of a pair of disk gangs, and gang frames provided with bolt holes centrally located, and also at their ends; a head plank overlying the gang frames and provided near its center and at each end with shifting bolt seats; a pole rigidly connected centrally with the head plank; bolts adapted to occupy any of said bolt seats in the head plank for pivoting the gangs near the pole or remotely therefrom, and draft bars connected with the pole and also directly connected with the gang frames, the organization being such that the disk gangs may be reversed, hinged at either end or at the middle, and located either adjacent to the pole, or remotely therefrom at the outer ends of the head plank.

4. The combination with a reversible disk gang, of double clod breakers suspended from a suitable support above the gang axle, and between the disks, both in front of, and at the rear of the gang axle, and also extended beneath the axle, substantially as described.

5. The combination with a disk gang, and a gang frame having journal box standards, of clod breakers secured to the gang frame at the front and at the rear of the standard, and extended to and in close engaging contact with the lower end of the standard, and serving not only as clod breakers but also as lateral braces for the standard, substantially as described.

6. In an adjustable harrow, a pair of disk gangs each provided with a series of disks uniform in diameter, and having an end disk larger in diameter than the other disks of the gang, substantially as described, said disks being so organized with an axle and frame, that the disks of uniform diameter, will penetrate to an equal depth, and the end disks cut more deeply into the soil than any of the others.
